UNITED STATES PATENT OFFICE.

NOAH L. WARNER, OF ASHLAND, OHIO, ASSIGNOR TO THE RELIABLE MATCH COMPANY, OF ASHLAND, OHIO, A CORPORATION OF OHIO.

MACHINE FOR PACKING MATCHES.

1,391,225.

Specification of Letters Patent. Patented Sept. 20, 1921.

Application filed July 9, 1920. Serial No. 395,141.

To all whom it may concern:

Be it known that I, NOAH L. WARNER, a citizen of the United States, residing at Ashland, in the county of Ashland and 5 State of Ohio, have invented certain new and useful Improvements in Machines for Packing Matches, of which the following is a specification, reference being had therein to the accompanying drawing.

10 This invention relates to machines for packing matches.

Heretofore it has been the practice to feed matches from the match-producing machine into and through the match-packing 15 machine with the matches in a large mass as they pass from entrance to discharge in the packing machine.

One serious objection to this has been that if anywhere along the line one or more 20 matches fired the fire would be free to travel throughout the entire mass and burn up a great quantity of matches.

The first object of my invention is to overcome this serious fault, and this I do 25 by subdividing the mass of matches into separate distinct quantities so that if a fire occurs it will be confined to the particular quantity of matches where it originated. In practice I have found this to be an im-

30 portant provision.

This subdivision of the matches into distinct quantities I find also facilitates feeding them into the match boxes, as I regulate the respective quantities to constitute each 35 about one-half a box. When each quantity arrives at a predetermined point it is discharged into its appropriate box and half fills the box, so that with each discharge each box is half filled and when each box 40 has received two discharges it is completely filled. This subdivision of the matches into distinct quantities facilitates and improves this operation.

In carrying out this first object, I employ 45 what I term a divider, an instrumentality which enters into the body of the mass of matches and separates therefrom a distinct quantity.

Another object of my invention is the 50 provision of what I term slides, being a part of the endless feeding mechanism by

which the matches are advanced through the trough or receptacle and which slides co-operate with the divider in the subdivision of the mass into distinct quantities of 55 matches.

Another feature of my invention comprises what I term gates, which are located in the discharge openings of the match trough and act to permit of the discharge 60 of each distinct quantity of matches when it arrives at the discharge opening in the trough. These gates perform the double function of forming a continuation of the trough bottom when closed and permitting 65 of the discharge of the distinct quantity of the matches when open; and also of acting to guide the matches into the mouth of the boxes.

Another feature of my invention comprises packing devices by which, as each 70 quantity of matches is fed into a box, the quantity is packed or settled down firmly and properly in the box, so that when the outer member of the box is slid over the 75 box proper the matches will not interfere and yet the box will be entirely full.

Another feature of my invention is the provision of means for spreading the opposite walls of the boxes somewhat apart so 80 that no matter whether the boxes have had their walls bent in by accident, as is often the case, the boxes will nevertheless readily slip over the rim which projects below and about the discharge opening. 85

In addition to these major features there are many other improvements which go to refine and complete my machine in its entirety.

In the accompanying drawings:— 90
Figure 1 is a side elevation of my machine;

Fig. 2 is an enlarged detail side elevation of a part of the machine showing particularly the feed trough, the blades and the operating mechanism therefor; and the box table and adjunct devices; 95

Fig. 3. is an enlarged partial section and partial elevation of the feeding trough, the blades and the divider by which the matches 100 are separated into distinct batches;

Fig. 4 is a similar view showing the di-

vider and the blades in their successive positions;

Fig. 5 is a sectional view of the feed trough, and the vibrating section, with the 5 agitating and pressing devices by which the matches are properly kept in motion and pressed into position as they are fed along;

Fig. 6 is a plan view of these devices;

Fig. 7 is a sectional view of the trough, 10 chain and blades showing a batch of matches about to be emptied;

Fig. 8 is a transverse sectional view, taken on the line 8—8 of Fig. 7, and looking in the direction of the arrows;

15 Fig. 9 is a plan view of one of the match boxes looking into it;

Fig. 10 is an enlarged detail view, partly in transverse section and partly in elevation, on the line 10—10 of Fig. 1, showing particularly the trough, chain drum, blades, 20 divider and mechanism for operating the blades and the divider;

Fig. 11 is a vertical sectional view showing one of the blades and the means for 25 locking it in different positions;

Fig. 12 is a plan view of the chain, one of the blades and the locking device therefor;

Fig. 13 is a sectional view on the line 13—13 of Fig. 1, showing one of the chain 30 drums, the chain and its blades, and the mechanism for feeding the chain step by step;

Fig. 14 is a vertical sectional view through this drum and the chain links;

35 Fig. 15 is a sectional view on the line 15—15 of Fig. 1, showing one of the chain drums and its adjacent parts, including the gate operating mechanism;

Fig. 16 is an elevation of one of the chain 40 drums and adjacent parts including devices for opening and closing the gates;

Fig. 17 is a detail sectional view on the line 17—17 of Fig. 1 showing part of the mechanism for imparting a rotary reciprocating and up and down motion to the box table;

Fig. 18 is a detail sectional view on the line 18—18 of Fig. 21 showing the step by step motion for the box table;

50 Fig. 19 is an enlarged plan view of the box table with the boxes thereon, the spreading device to spread the walls of bent-in boxes and the packing devices for packing the matches in the boxes as they are filled;

55 Fig. 20 is a detail view of the mechanism for holding the table top in locked position while the boxes are being filled with matches;

Fig. 21 is a detail view showing the means 60 of retaining the step by step ring with its operating mechanism in dotted lines;

Fig. 22 is a plan view showing the lever and cam used to elevate the box table and also rotate it step by step;

65 Fig. 23 is an end view of the box spreader

and of a box which is about to pass under the spreader;

Fig. 24 is a detail view of the packing devices;

Fig. 25 is a plan view of the several shafts 70 and the gearing and cams carried and operated thereby; and

Fig. 26 is a detail sectional view illustrating the means of driving from the master shaft to the line shaft. 75

In the accompanying drawings the present invention is well illustrated. At the right of Fig. 1 is illustrated part of a match-making machine, from the trough 1 and endless feed chain 2 of which the 80 matches are delivered to the machine illustrated at the left, which comprises my invention. The matches first enter the inclined chute 3, of my machine, which is given a shaking motion to facilitate the 85 movement of the mass of matches which are gathered into it. This motion is imparted to it by its connection with the trough 1 of the other machine which itself has a vibrating or reciprocating motion. 90

This chute 3 is equipped with a device 4 for spreading the mass of matches. This spreader is composed of a pair of rods loosely hung at one end on a cross pin 5 and at the other end on a shaft 6 having rollers 7 which travel back and forth on plates 8 secured to the sides of the chute 3. The spreader is given a back and forth motion by the shaft 6 and an up and down motion by sliding on the rod 5 and said shaft. As the matches come down the chute in a thick mass, their heads all in one direction, the spreader acts to somewhat flatten out the mass and cause the matches to lie more evenly together. 95

100 The chute is further equipped with a pusher comprised of a plate 9 having a projection 10 to enter between the matches and facilitate the action of the pusher in advancing the body of matches onward. The shaft 6 before referred to passes through or is otherwise connected with the plate 9 so as to receive a reciprocating motion and so as to support that portion of the pusher. The pusher is reciprocated and tilted on the 110

shaft 6 by a crank pin 11 carried by a disk 12 on a shaft 13 mounted in a suitable bearing 14 supported by a standard 14^a secured to the bed 23 and having a pulley 15 by which it is driven through a cord belt 12^a 115 (Figs. 1, 5 and 6) operated by a groove pulley 12^b on a master driving shaft 15^a mounted in brackets 16^a secured to the bed of the machine. The wrist pin enters a bearing 16 carried by the pusher so that 120

when the wrist pin is rotated it reciprocates the pusher and at the same time tilts it on the shaft 6. The direction of rotation of the wrist pin is counterclockwise so as to raise the lower end of the pusher out of 125 130

contact with the matches on the return stroke of the pusher.

The chute 3 is further provided with a presser for holding down or depressing the mass of matches while the divider, to be presently mentioned, is entering the mass. This presser is comprised of a pair of bars 17 pivoted at 18 on studs supported by plates 19 secured to the chute. This presser 10 swings on pivots and by its gravity sufficiently presses upon the matches to hold them from being lifted out of the chute and trough, while the divider is entering the mass of matches.

15 As stated, one end of the chute 3 is connected with the trough 1 of the match making machine. The other end is supported upon a rock arm 20 carried by a shaft 21 supported on a standard 22 mounted on the 20 main frame 23.

This frame comprises a heavy plate of metal supported upon legs 24 braced by members 25. It is on this bed 23 that the functional mechanisms are carried.

25 A match-carrier trough 26 is suitably supported on the standards 22 and 27. The matches are fed into this trough from the chute 3 over a thin bridge plate 28, see Figs. 1, 3, 4 and 5. The vibration of the chute 3 and the action of the spreader 4 and pusher 9 cause the mass of matches to move into the trough 26. After the mass of matches has moved a short distance into this trough 26 a portion of the mass is divided off from 35 the remainder. This important function is performed by a device I call a divider. (See Figs. 3 and 4 particularly.) The chute 3 has in its bottom a slot 29 in line with a similar slot 30 in the bottom of the trough 26. After the mass of matches has moved a short distance into this trough 26 a portion of the mass is divided off from 40 the remainder. This important function is performed by a device I call a divider. (See Figs. 3 and 4 particularly.) The chute 3 has in its bottom a slot 29 in line with a similar slot 30 in the bottom of the trough 26. A divider 31 enters this slot when in 45 normal or first position, as shown at the right in Fig. 3. Its operating devices are so timed that the divider will rise and enter the slot 29 to its second position, as shown in dotted lines in Figs. 3 and 4 and pass up through the body of matches. This separates a given quantity *a* of matches from the rest. The divider then moves along the trough 26 until it reaches the third position 50 shown in dotted lines, by which time it will have partially opened, its members slightly parting. By this time one of the carrier blades 33 will have descended to the position shown at *d*. (Fig. 4.) Both the divider and this blade will now travel along until the divider reaches the fourth position shown in dotted lines and the blade reaches the position shown at *e*. During these movements the quantity of matches *a*, 55 which has been cut off from the oncoming quantity at the right of the divider in its second position, will have been moved first to the position shown at *b* and thence and now to the position shown at *c*.

60 The next step is the withdrawal of the

divider from this fourth position to the fifth position shown in full lines in Fig. 4. It will then return to the first position shown in Fig. 4. This cycle of operations will continue as the machine is operated.

70

In this way one succession of quantities of matches after another is divided off from the mass and each quantity placed in position to be embraced between each two slides.

When the divider is withdrawn from the 75 fourth position to the fifth the matches in the batch now positioned at *c* will settle down and fill in the space between the two adjacent blades 33, which thus constitute a pair of match conveying devices.

80

The detail construction of the particular form of divider illustrated and the mechanism by which these motions are imparted to the divider will now be given.

The divider comprises a pair of arms or 85 levers which meet to form a point at 34 and are pivoted at 35 to a head 36 mounted on a slide 37, in turn carried by a support 38 sustained by a column 39 mounted in bearings 40 suitably mounted on the base 23. A 90 spring 41 acts on the divider arms to keep them normally closed at their upper ends. They commence to spread apart at the time when one of the slides 33 is approaching them and continue gradually to open until they reach the fourth position shown in Figs. 3 and 4, by which time the adjacent slide will have entered between them. This is done by means of a shaft 42 carrying an eccentric 43 which when rotated spreads the 95 arms apart. A crank 43^a on the shaft 42 carries a roller 43^b which contacts with a cam plate 43^c secured to the trough 26. This contact of the roller 43^b with this cam plate commences at the time when the divider has 100 reached the third position shown in Figs. 3 and 4. As the divider moves on to the fourth position the contact of the roller 43^b with the cam plate 43^c continues.

105

When the divider has been withdrawn 110 from the trough the roller 43^a will have passed beyond the cam plate 43^c when the spring 41 will snap the divider members together, throwing the crank 43^a back to normal position.

115

Guard plates 44 are attached to the divider to prevent any possible match or piece of a match that might escape from the chute 3 or trough 26 from getting caught in any of the moving parts connected with the 120 divider. These guards are made of thin spring metal so that they will yield should they touch any adjacent part and thus shake the divider to dislodge any small fragments of matches or the inflammable head.

125

I will now refer to the mechanism by which the divider is moved vertically into and out of the chute and trough and moved horizontally from one position to another. This mechanism is best shown in Figs. 1, 3 130

and 10. To effect the vertical adjustment of the divider the shaft 39 is moved up and down. Its lower end terminates in bifurcated members 45 which straddle a line 5 shaft 145 carrying a cam 47 which acts on a cam roller 48 connected to the bifurcated members 45, so that when the cam is rotated it elevates and lowers the shaft and with it the support 38 for the slide 37 on which is 10 mounted the head 36 of the divider. The throw of this cam is so timed with reference to the movements of the chain carrier that the divider will rise and enter the chute and descend and withdraw from the trough 26 15 at the proper time.

The means for giving the divider its back and forth or horizontal movement comprises a pitman 49 having one end slidingly connected with the head 36 by means of a slide 20 50 engaging with the head. This pitman 49 is connected at its other end with a carriage 51 mounted on a slide 52 secured to the trough 26.

A lever 53 is vibrated to impart a reciprocating motion to this slide 51 and thence to the pitman 49. The stroke is commensurate with the horizontal travel of the divider. The lever 53 is mounted in a standard 30 54 on a shaft 55 and at its lower end is slotted to fit over a roller 56 mounted on a shaft 57 carried in a bearing 58, supported on the slide 59 adapted to travel on fixed ways 60. In order to impart a reciprocating motion to the slide 59 and thereby an oscillating motion to the lever 53 to operate the pitman 49 and slide 51, the slide is provided with a bracket 61, (Fig. 13) which carries rollers 62 (Figs. 1 and 13). These rollers are engaged by the cam track 63 of 35 a cam wheel 64. The rotation of this cam causes the slide 59 to reciprocate and thereby oscillate the lever 53. The cam wheel 64 is mounted on the line shaft 145 driven by a belt pulley 65.

45 Referring again to the slide 51 it will be seen that it carries a detent 66 adapted to engage with the feeding chain in order to advance the chain with a step by step motion.

I will now refer to the endless chain mechanism. It comprises two polygonal drums 50 67 mounted, respectively, on shaft 68 carried in bearings on the upper end of the column 22 and the shaft 69 carried on the upper end of the column 70. A beam 71 is carried by 55 these shafts 68 and 69 and serves as a sort of bridge for the support of the upper branch of the endless chain. This chain is comprised of links 72 and interconnected by frames 73 having lugs 74 which by rivets 75 60 are connected to the links 72. One link on either side is pivoted to the adjacent frame and the adjoining link is rigidly fastened, in any suitable manner, to the frame, as indicated in Fig. 13.

65 Each of these frames has an opening be-

tween its walls and in each opening there is 70 slidably mounted the blades 33 having sockets 77 into which is adapted to snap a ratchet device composed of a ball 78 urged by a spring 79. The sockets 77 are so located that the slide will be engaged by the ratchet at the two extremes of its adjusted position, its inner and outer positions.

The function of these blades carried by 75 the chain is two-fold. They receive between each two of them the distinct separate quantities of matches, in the manner hereinbefore described, and they convey these quantities of matches through the trough 26 to the points of discharge, as will 80 presently appear.

In order to adjust the blades radially so 85 that as they approach entrance into the trough, as at the right hand end of Fig. 1, and be in readiness to be successively adjusted down into the trough and in between the arms of the divider, certain slide-operating mechanism is employed.

This mechanism comprises a pair of vertically sliding bars 80 and 81 which are 90 connected together at the point 82 by suitable screws or bolts. These bars have arms 83 and 84, respectively, the latter adapted to act on the successive slides and adjust them inwardly, as shown in Figs. 1 and 10, and 95 the former to likewise act on the slides to adjust them outwardly and into the trough 26, as shown in Figs. 1 and 4.

Turning now to Fig. 10 the mechanism for 100 operating these bars is shown. It comprises a rock arm 85 connected at one end by a pivoted link 86 to the bar 80 and at the other end to a pitman 87 whose lower end is pivoted to an actuating arm 88. The arm 85 is supported on a pivot 89 sustained by a 105 standard 90 while the actuating arm 88 is sustained by a pivot 91 carried by a bracket 92. These fixed parts are secured to the bed 23.

In order to reciprocate the bars 80 and 81 110 the actuating arm 88 is operated by a cam 93 which is mounted on the line shaft 145. The throw of this cam is so configurated and timed that it will cause the descent of the slides 33 at the proper time with relation to 115 the movements of the dividers, as more fully appears hereinbefore. Suitable guides 94 are employed for sustaining the bar 80.

I will now refer to the devices employed 120 in the discharge of the separate batches of matches. In the first place the trough has two openings in the bottom, one at the point 95 and the other at the point 96. Each batch of matches is equal to half a box full. Two batches will fill a box. A batch is discharged at each of the exits 95 and 96. At 125 each exit there is provided a pair of gates 97 hinged by means of trunnions 98 mounted in plates 99 secured by screws 100 to the sides of the trough.

When the gates are closed they constitute in effect a continuation of the bottom of the trough. When opened they discharge the batch of matches between the two slides, 5 as particularly shown in Figs. 7 and 8.

One means of opening and closing the gates, which preferably are opened and closed at the same time, comprises the mechanism more particularly shown in Figs. 1 10 and 2. It consists of pinions 101 mounted on the trunnions 98 and engaged by slideable rack bars 102 which travel in suitable guides or ways 103. These racks and pinions are alike for both pairs of gates. The racks 15 for one pair are connected to the racks for the other pair by an intermediate rod 104, so that both pairs of racks are operated by the vibrating lever 105 pivoted at 106 and connected to one pair of racks by a stud 107 20 extending from an extension 108 on one of the racks. A slot 109 in the lever 105 compensates for the motion between these parts. This lever 106 is actuated by a cam 110^a mounted on a driving shaft 111. An extension 112 of the lever 105 carries a roller 113 25 which is engaged by the cam 110 to vibrate the lever 105 in one direction so as to move the racks and partially revolve the pinions 101 to open the gates. A spring 114 30 connects at one end to the bed 23 and at the other to the extension 112 of the lever 105 operates the lever in the opposite direction and reverses the movement of the racks so as to close the gates. It will be understood 35 that the racks engage the respective pinions at diametrically opposite points so that all the gates will open by one movement and close by the other.

It will be understood that the movements 40 of these parts are timed to agree with the arrival of the boxes that are to be filled at points under the gates.

Referring again to the shaft 111 it is to be noted that it is mounted in brackets 115 45 secured to the under surface of the bed 23. The means by which this shaft 111 is rotated will be hereinafter described.

In Fig. 7 a pair of gates is shown closed in full lines and open in dotted lines. 50 About each discharge opening in the trough is placed a discharge chute or guide for the matches composed of two plates 116, one at each side of the opening. Between these guides the gates swing open. The descending quantity of matches is thus guided by the combined action of the plates 116 acting on the ends of the matches and the gates 97 55 acting on the sides of the matches. The boxes, an example of which is shown at 117 in Figs. 8 and 9, are successively brought to a position where they embrace and overlap the guide flanges 118. In this way the batches of matches are properly guided to and delivered into the boxes.

60 Referring again to the racks and to Fig.

8 it will be seen that a cover plate 119 is secured to one side of the trough 26 by screws 120 so as to inclose the racks and pinions. A strip 121 is preferably secured to one side of the trough 26, as shown in 70 Fig. 8, to fill in the space between the side of the trough, and the cap 119 to exclude dust and dirt that might otherwise get to the racks and pinions.

I will now refer to the mechanism by 75 which the boxes are successively presented to the discharge openings in the trough. See particularly Figs. 1, 2 and 17. This mechanism comprises a table 122, adapted to be rotated, step by step, and to be elevated to and lowered from the discharge openings. The boxes are placed on this table between holders 122^a in the nature of flanged strips. See Fig. 19. At the proper time, or when both pairs of gates are opened the table 80 moves upward and presents one box 117 under each opening, as shown in Fig. 8. In order that the table shall have these two motions, the rotatable and perpendicular, it is mounted on a sleeve 123 which rotates and 85 slides on a hollow bearing 124 secured to the bed 23. A disk 125 is secured to the sleeve 123 so that when the disk is rotated it rotates the sleeve and thereby the table. The devices for rotating this disk comprise a ring 90 95 126 mounted on the bed 23 under clips 127 and against the base flange of the bearing 124. The disk 125 has a series of peripheral notches 128 into any one of which an actuating arm 129 may enter, this arm being secured to the operating ring 126 so that a rotary movement of this ring will be imparted through the arm 129 and the disk 125 to the sleeve 123 and thence to the table 122. This ring 126 is given a rotary 100 105 reciprocating motion by means of a lever 130 pivoted at 131 to the under part of the bed and at the other end connected by a link 132, (see Figs. 17, 21 and 22), to the ring 126. A screw 132^a connects the link with the 110 lever. The other end of the link is connected to the ring 126 by a bolt 126^a which passes through a slot 127^a in the bed 23. (See Figs. 17, 21 and 22.) The lever 130 is swung in one direction by a cam and in the other by a spring 130^a. When the cam moves the lever the table is rotated a step. When the spring moves the lever the table with the disk 125 will have been elevated to a point which will break the engagement between the disk 125 and the arm 129. The return movement of the lever and therefore of the ring 126 and the arm 129 has no effect upon the table. This cam referred to comprises a body 133 mounted on the shaft 111 and having a cam surface 134 which acts on the lever 130 through a roller 135 carried by a stud shaft 136 secured to the lever 130. This cam surface 134 thereby shifts the lever from side to side and through its link 115 120 125 130

132 gives the rotary reciprocating movement to the ring 126. Just after the box table has been given its reciprocatory and vertical movements above described, it is held from 5 further rotation by the standard 129^a which is secured to the base 23, while at the same time the boxes are being filled and the ring 126 returns to normal position.

Referring now to the mechanism for elevating and lowering the table 122 attention is directed to the shaft 137, (Fig. 17), which is mounted in bushings within the sleeve bearing 124. The table turns freely on this shaft, ball bearings 138 and 139 being preferably employed to reduce friction so that when the table is rotated by the means already described it turns freely on the shaft 137 whose function is to raise and lower the table. To impart the movements to the shaft 20 137 it is equipped with a roller 140, as shown in Figs. 1 and 17, which travels in a cam way 141 whose configuration and position act to raise and lower the shaft at the proper time, to present the table to and remove it 25 from the trough 26 at the time the boxes are being filled and presented under the gates. The lower end of the shaft 137 is extended down and bifurcated, as shown in Figs. 1 and 17, at 142, the bifurcation embracing the shaft 111 to aid in guiding the shaft 137 in its vertical movements.

Referring now to Fig. 25 the arrangement of the several shafts with the gears and cams will be seen. The master drive shaft 35 15^a has a pinion 143 preferably having twenty-three teeth which meshes with a gear wheel 144 preferably having sixty-six teeth. This gear is carried by a line shaft 145 supported in suitable bearings carried 40 by the bed 23. This shaft 145 carries the cams 47 for elevating the dividers, the cam 93 for operating the rods 80 and 81 which actuate the blades 33 and the cam 64 which through intermediate devices advances the 45 endless chain step by step and reciprocates the dividers. A gear 146 on the shaft 145 meshes with a gear 147 on an idler shaft 148 carrying a pinion 149 which meshes with the gear 110 on the shaft 111. The gears 50 146 and 147 are of equal diameter while the pinion 149 has twenty teeth as compared with forty teeth in the gear 110 for the purpose of reducing the speed of the shaft 111. This shaft also carries the cam body 133 55 which carries the cam surface 134 and the cam way 141. (See Fig. 17.)

By slowing down the speed of the shaft 111 and its cams 110^a, 134 and 141 motions of the box table—rotary and vertical—are slowed down. This is done because on each 60 positioning of the table two batches are emptied at a time, while on the other hand the chain and slides advance only one batch at a time. To enable the chain to keep up 65 the supply of batches of matches, one batch

being advanced with each movement of the chain, with the delivery of two batches of matches at a time, the speed of the table and its presentation of boxes must be slowed down to a less speed than that of the advance 70 of the chain.

Referring to Figs. 15, 19 and 23 it will be seen that I provide a device for spreading the side walls of the boxes should they be, as is often the case, bent inwardly to an extent 75 that would interfere with their readily feeding over the guide flanges 118, as shown in Fig. 9. This device comprises a head 150 having inclined sides 151 which readily enter the boxes, the head being secured by 80 an arm 152 to the column 70. This spreader is so located that it stands immediately over each successive box as the boxes are moved step by step. When the table 122 is raised the spreader will enter the box beneath it 85 and force the sides outwardly to overcome the defective inward position of the sides. When the table descends the box withdraws from the spreader. Then when the box reaches the adjacent filling station it is in 90 condition to readily pass over the guide flanges 118.

At 153 in Fig. 19 are shown a box adjuster comprised of a spring arm which is positioned to be touched by any box that has 95 been placed too far outward. This contact with the box causes the adjuster to shift the box slightly inward to make it fit in the corners of the box holders 122^a.

The next feature to which I would direct 100 attention is that of a device I term a settler. (See Figs. 19 and 24.) Its function is to settle the matches down in the boxes so that they will lie properly therein and will not project above the top to interfere with the 105 sliding of the cover member of the box over the body. This settler may be made to act on the matches in one or more boxes. In the exemplification shown in the drawing the settler is constructed to act upon the matches 110 in two boxes, one a half filled box and the other a fully filled box. This device comprises a shaft 154 supported at one end in a bearing 155 carried by the column 27 and at the other end by a vibrating lever 156 pivoted at 157 to the trough 26 and connected at the other end to a pitman 158 which extends alongside of the trough 26 and is attached to the vibrating chute 3 at the point 159. In this way a quick reciprocating motion is given the shaft 154. It is positioned to lie over boxes which have been half filled and wholly filled. This shaft carries two settler heads 160 for settling the matches in a half filled box and 170 for settling the 125 matches in a fully filled box. This head comprises a body 161 serrated along the lower face so that it will lightly take hold of the matches and settle them down as it reciprocates over and against them in short 130

rapid strokes. It has projections 162 which are slotted to fit over the shaft 154. It is retained in proper position by a collar and set screw device 163. The slots permit the 5 head to give up and down to avoid pressing upon the matches too severely.

Immediately after a box has been half filled and while another box is being so filled it will stand under the settler 160 which will 10 act on the matches therein, while immediately after a box has been fully filled it will pass under the settler 170 where it will stand while the next box is being fully filled, during which period the matches therein will 15 also be settled.

From the foregoing detail description it is thought that the mode of operation of the machine as a whole as well as the operation of the individual parts will be fully understood. It will be noted, however, that for 20 the first few minutes after the machine is started every other batch of matches will be discharged from the discharge station *g* before any of the batches are delivered from 25 the station *f*. These few batches are caught in any convenient way, say in a box or other vessel, and refed to the machine by being placed in the chute 3. But as soon as the first batch reaches the discharge station *f* 30 then from that time on batches will be delivered from both stations *g* and *f* at the same time, those from the station *f* filling the first half into the boxes and those from the station *g* filling the second half into the 35 boxes.

By observing Fig. 19 it will be seen that the box table 122 rotates in the direction of the arrows, the boxes coming in succession to the station *f* being half filled by one batch 40 and those coming to the station *g* being completely filled by another batch. The operator will preferably stand at the point *h* so as to pull or push each box as it comes along into a chute *i* and to replace it by another box at *j*. In this way the discharge 45 and supply of boxes are kept up.

It will further be noted that by reason of the proper timing of the operating mechanism as before described the box table 122 50 will at each step of its rotation present a box under each discharge station; and also that the table will rise the proper height as each box is properly positioned so as to set the boxes over the guide flange 118, (Fig. 55 8). Also, that the gates will automatically open on the final positioning of each box and will automatically close as such boxes are unpositioned, so as to bridge over the discharge opening in order that the succeeding 60 batch of matches destined to the station *g* will be supported in passing over station *f*. It will be remembered that the carrying chain travels twice as fast as the rotation of the box table which is for the 65 purpose of providing two batches of matches

for discharge for every one new positioning of the table.

This feature of the relative speed of movement of the carrying chains and the box table is important as it enables me to discharge two distinct batches of matches at a time. And in order to separate the matches into separate batches, that this may be done, the divider is of major importance. Likewise, are the blades of prime importance as 70 they co-operate with the divider by maintaining each batch in a separate state after it has been divided off from the mass of matches.

This sub-division of the matches into separate batches also is of great importance in respect of being a safety measure by which any accidental fire is confined to the particular batch in which it may originate, besides affording that other advantage of delivering two measured quantities at the same time from the stations *f* and *g*. 80

While I have shown and described certain constructions as embodying my invention, it will be understood that these have 90 been shown for purposes of illustration only, and that I do not desire to be limited to such details, as obvious modifications will occur to a person skilled in the art.

Having thus fully described my invention, what I claim as new and desire to secure by Letters Patent, is:—

1. In a match-packing machine, the combination, of a divider adapted to enter into and withdraw from a quantity of matches 100 for segregating separate batches of matches, with match-conveying means including devices to receive each batch and maintain its segregation.

2. In a match-packing machine, the combination, of a divider adapted to enter into and withdraw from a quantity of matches for segregating separate batches of matches, 105 with match-conveying means including devices to receive each batch and maintain its segregation, and discharge devices to deliver each batch separately.

3. In a match-packing machine, the combination, of a divider adapted to enter into and withdraw from a quantity of matches 115 for segregating separate batches of matches, with match-conveying means including devices to receive each batch and maintain its segregation, and discharge devices each located at a separate station to deliver each a 120 separate batch.

4. In a match-packing machine, the combination, with a chute, and a divider adapted to successively enter into and withdraw from the chute to segregate successive 125 batches from the mass of matches, of a match-conveying means including a trough and slides, the latter adapted to receive between each two a batch of matches so divided off and maintain its segregation. 130

5. In a match-packing machine, the combination, with a chute, and a divider adapted to successively enter into and withdraw from the chute to segregate successive 5 batches from the mass of matches, of a match-conveying means including a trough and slides, the latter adapted to receive between each two a batch of matches so divided off and maintain its segregation, the 10 trough having a plurality of discharge openings, and gates to open and close said openings.

6. In a match-packing machine, a vibrating chute to deliver matches en masse, a 15 divider to segregate batches from the mass, a trough and a succession of traveling slides to receive each batch divided off and to convey all the batches, the trough having discharge stations and devices to open and 20 close the same, and a box-support adapted to present boxes in succession at said stations.

7. In a match-packing machine, the combination, with a chute, a divider, a trough 25 having a plurality of discharge stations, and gates to open and close said stations, an endless carrier having a series of slides adapted to be projected into the trough and to receive between each two a segregated 30 batch of matches delivered by the divider, and a box table having a rotatable and up and down adjustment and adapted to successively present one box at a time to each discharge station, and operating mechanism 35 adapted to actuate these several elements in order.

8. In a match-packing machine, the combination, with a chute and a conveying trough, a divider adapted to enter therein 40 and divide off separate batches of matches, an endless carrier having a series of slides adapted to receive between each pair a segregated batch and to deliver the batches in succession to a plurality of discharge stations, devices to actuate said slides, gates to 45 open and close the discharge stations, a box table adapted to rotate step by step and to raise and lower two delivery boxes in succession to said stations, and actuating devices for the endless carrier to move it step by step to present each batch of matches to a discharge station, and devices to actuate the divider, the box table and the gates in coördination.

55 9. In a match-packing machine, a bed, a box table and operating mechanism to rotate it step by step and to raise and lower it, columns on the bed, a conveying trough and chain drums supported by the columns, 60 mechanism to move the chain step by step, slides carried by the chain, devices to adjust the slides in and out, gates in discharge openings in the trough, devices to open and close the gates, a chute, and a divider 65 adapted to enter into and move within the

chute and trough to segregate and deliver batches of matches from the mass, and means to actuate the divider.

10. In a match-packing machine, a bed, a box table and operating mechanism to rotate it step by step and to raise and lower it, columns on the bed, a conveying trough and chain drums supported by the columns, mechanism to move the chain step by step, slides carried by the chain, devices to adjust the slides in and out, gates in discharge openings in the trough, devices to open and close the gates, a chute, a divider adapted to enter into and move within the chute and trough to segregate and deliver batches of 70 matches from the mass, means to actuate the divider, and settling devices adapted to enter the boxes on the table to settle the matches therein, and devices to operate the settling devices after each box receives each 75 batch of matches.

11. In a match-packing machine, the combination, with a receptacle for containing matches en masse and in batches, the receptacle having an opening, of a divider 80 adapted to transversely enter the receptacle through said opening to divide off batches of matches and to travel in the receptacle, then withdraw, and reverse its direction, and devices to so operate the divider.

12. In a match-packing machine, the combination, with a receptacle in the nature of a trough, a divider adapted to transversely enter therein and divide off a batch from a mass of matches, devices to cause the divider to enter, travel in and withdraw from the receptacle and reverse its direction, and a succession of match-conveying devices adapted to successively enter the receptacle and to receive between them batches of 100 matches divided off by said divider.

13. In a match-packing machine, the combination, with a chute and a trough having a slotted bottom, and an endless chain having a succession of slides, and means to project the slides successively into the trough, of a divider, and devices to project the divider through said slotted bottom and to cause it to travel to divide off and convey a batch of matches, and other devices to open 110 the divider to permit a slide to enter between its members.

14. In a match-packing machine, the combination, with a divider composed of openable members, of a slide adapted to enter between said members, and devices to operate the divider to present it to the slide and to move it therefrom, and other devices to open and close the divider.

15. In a match-packing machine, a 125 trough having a slot and a cam device, a divider, means to project the divider into and out of the trough and into contact with the cam surface to open the members of the divider.

16. In a match-packing machine, the combination, with a divider, of a slide on which it is mounted, such slide being adapted to have vertical and horizontal motion, and means to impart to the slide and to the divider both of said motions. 70
17. In a match packing machine, the combination, with a divider, and devices to operate the divider transversely and longitudinally, of an endless chain and its slides, mechanism to advance the chain step by step, and other mechanism to actuate the divider-operating devices to cause the divider and step by step devices to act 75 in proper unison. 15
18. In a match packing machine, the combination, with a divider and its slide capable of vertical and horizontal movement, and devices to impart such vertical movement, of an endless chain having slides, a 20 detent device to advance the chain step by step, a connection between the detent devices and the divider slide, and a common actuating device for said slide and detent 25 devices. 25
19. In a match-packing machine, the combination with a chute for conveying matches, of an endless conveying chain, slides mounted therein, and devices to actuate a slide inward and another slide outward. 30
20. In a match-packing machine, the combination with a chute for conveying matches, of a pair of chain drums, a conveying chain mounted thereon, slides mounted in said chain, and movable bars, one adapted to move the slides toward a drum center and the other to move the slides from the drum center. 35
21. In a match-packing machine, the combination with a chute for conveying matches, of an endless conveying chain comprising links, a frame connected with the links, a slide mounted in the frame, and 40 detent devices to hold the slide in adjusted positions. 45
22. In a match-packing machine, the combination, with a chute, of a pusher operating therein to advance the matches, a presser to act on the matches, and a spreader also to 50 act on them. 55
23. In a match packing machine, the combination, with a conveying trough having discharge openings, gates mounted in such openings and devices to open and close said gates, of a box table and devices to rotate it step by step and to raise and lower it to present boxes in succession to said gates. 60
24. In a match-packing machine, the combination, with a substantially horizontal conveying trough having a plurality of discharge openings, one opening located near one end of the trough and the other remote from such end, of a pair of gates mounted 65 in each opening and adapted when in hori- zontal position to close the openings and to open them when in vertical position, a common operating device connected to said gates, and means to actuate such device. 70
25. In a match-packing machine, the combination, with a substantially horizontal conveying trough having discharge openings, of a pair of gates mounted in each opening, said gates when in closed position being substantially horizontal and when in open position substantially vertical, a pinion on each gate shaft, a rack adapted to operate each pair of pinions, a connecting rod between the racks and actuating devices connected to one of the racks to operate the 80 same. 75
26. In a match-packing machine, the combination, with a feed trough having discharge stations and controlling gates, of a box table adapted to carry a series of boxes 85 and present them in succession to said discharge stations, devices to raise and lower the table, and other devices to rotate it step by step. 80
27. In a match-packing machine, the combination, with a feed trough having discharge stations and controlling gates, of a box table adapted to carry a series of boxes 90 and present them in succession to said discharge stations, devices to raise and lower the table, other devices to rotate it step by step, and settling devices adapted to enter the boxes and settle the matches after each box moves away from the discharge station. 95
28. In a match-packing machine, a box 100 table, a vertical shaft therefor, a cam adapted to raise and lower said shaft, and an actuating device rotatably connected with the table, and a cam to impart locomotion to said device, whereby the table 105 may be raised and lowered and given a rotative movement. 100
29. In a match-packing machine, a box 110 table, a vertical shaft therefor, a cam arranged to raise and lower the shaft, a notched disk connected with the table, an arm adapted to enter either of said notches, a rotatable ring connected to said arm, a lever connected to said ring, a cam face to operate the lever in one direction, and a 115 spring to operate it in the other, whereby said table may be raised and lowered and given a step by step rotation. 110
30. In a match packing machine, the combination, with a trough having a match-discharging opening, of a rotatable box supporting table beneath said trough-opening, 120 holders thereon for the boxes, and a device to shift the boxes into final position on said table under said opening with each rotative 125 step. 120
31. In a match-packing machine, the combination, with a conveying trough having filling stations, of a rotatable box table beneath the trough adapted to successively 130

place boxes under the stations and a settling device above the table and comprising a vibrating rod having two heads to enter, respectively, the boxes that have passed 5 from the said filling stations.

32. In a match-packing machine, a settling device comprising a vibrating rod, a slotted head hung on the same and adapted to settle the matches with which it 10 comes in contact.

33. In a match-packing machine, the combination, with vertical rods having lateral

projections adapted to engage with conveying slides, of a rocking arm connected to one of the rods at one end, a pitman 15 connected to the other end of the arm, a lever connected to said pitman, and a cam acting on the other end of the pitman to impart motion, whereby said vertical bars are operated up and down.

In testimony whereof, I affix my signature.

NOAH L. WARNER.
